(57) **CLAIM**

The ornamental design for a roofing tear out shovel, as shown and described: shovel blade rotates around center axis, easy- tear out roofing materials and nails

DESCRIPTION

FIG. 1 is a perspective view of a roofing tear out shovel, showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side view thereof; and

FIG. 7 is a left side view thereof; and,

FIG. 8 an enlarged and fragmentary perspective view of the lower portion of the roofing tear out shovel, showing my new design.
